BEAM CENTERING APPARATUS

Paul Heller, Richmond Hill, N.Y., assignor to Westinghouse Electric Corporation, East Pittsburgh, Pa., a corporation of Pennsylvania

Application April 26, 1956, Serial No. 580,861

7 Claims. (Cl. 313—76)

The present invention relates to apparatus for centering the electron beam on the screen of a cathode ray tube and, more particularly, to beam centering apparatus for centering of the raster on the screen of a cathode ray tube of a television receiver.

In a cathode ray tube especially of the type used for television purposes it has been found very desirable to provide some means for centering or adjusting the un-deflected position of the electron beam relative to the screen of the cathode ray tube in order that the images may be reproduced correctly centered on the screen area. One arrangement that is suitable for accomplishing beam centering comprises two annular magnets, each permanently magnetized across its diameter. The two magnets are disposed side-by-side and are mounted for independent rotation about the neck of the cathode ray tube. By rotating either or both of the magnets, the strength and direction of the resultant magnetic field along the axis of the tube neck may be changed in accordance with the relative positions of the magnets.

In my copending U.S. application, Serial No. 531,720, filed August 31, 1955, and entitled "Retaining Device," there is described and claimed a device which serves to retain electron beam controlling apparatus of a cathode ray tube, such as a deflection yoke, at a predetermined location along the neck of the tube. This device may also serve as a mounting for annular permanent magnets used for electron beam centering. According to that application, the annular magnets are mounted adjacent to the base portion of the retaining device and are rotatable about the axis of the cathode ray tube neck. The annular magnets are held against the base portion of the retaining device by the utilization of a pair of tabs that are integral with the base portion. The tabs are rolled over after the magnets are suitably positioned. Also, according to that application, springs can be used in place of the tabs to hold the beam centering magnets adjacent to the base portion of the device.

It is an object of the present invention to provide an improved annular permanent magnet means for affording beam centering in a cathode ray tube.

It is another object to provide an annular permanent magnet beam centering means which is simpler in construction than those of the prior art.

It is still another object to provide an annular permanent magnet beam centering means which does not utilize an external or non-integral magnet holding device.

Figure 1 is a side elevational view of a beam centering means mounted on the neck section of a cathode ray tube; and

Fig. 2 is a rear view of Fig. 1.

Referring to the drawings, the cathode ray tube shown in outline form is indicated by the numeral 10 and is comprised of a neck portion 12 and a flare or bulb portion 14. The cathode ray beam of the tube 10 is deflected by means of a deflecting unit or yoke indicated by the reference numeral 16. The yoke is placed around the neck portion 12 of the tube and is slid along that

2

neck portion to an appropriate position, usually right up against the flare portion of the tube.

A retaining device indicated by the reference numeral 18 is comprised of a base portion 20 and integral flange portions 22 and 24. The base portion 20 has a central aperture to which the neck portion 12 of the tube is adapted to pass. The flange portion 22 is provided with a plurality of slots 26 which are utilized to key the retaining device 18 to the deflection yoke 16 to insure that there will exist no relative movement between the two. The flange portion 24 is segmented and a plurality of segments 28 extend longitudinally and outwardly from the base portion 20. The segments 28 are made of a flexible material and are made to taper inwardly towards their free ends. The segments 28 are laterally spaced from each other a distance less than the diameter of the neck 12 so that when the retaining device 18 is placed on the cathode ray tube, the segments 28 will closely engage the neck. The retaining device 18 will substantially prevent the yoke 16 from rotating about the neck 12 and it will also retain the yoke 16 at the appropriate location along the neck of the tube. It is most desirable that the device 18 be somewhat flexible in order that the segments 28 will be expanded laterally and outwardly from the axis of the neck 12 so that the segments will closely engage the neck. The segments 28 are also chamfered at both ends as shown at 30 in order to allow the yoke 16 to slip on and off the neck 12 of the cathode ray tube 10 with a minimum of interference with the base structure or socket (not shown) of the cathode ray tube 10. The longitudinally extending segments 28 have a sufficient length so that when the yoke 16 is properly positioned on the neck 12 of the tube, a clamping or mounting ring 32 may be placed over the segments and tightened by means of screw 34 so as to securely lock the retaining device 18 and the yoke 16 to the neck 12 of the cathode ray tube. The segments 28 are wedge-shaped so that when the retaining device 18 is placed upon the neck portion 12, their outer surfaces will be parallel to the longitudinal axis of the cathode ray tube and there will be a minimum tendency for the clamping ring 32 to slip off the segments.

The retaining device 18 is shown as a rear or back cover for the deflection yoke 16. The device 18 is preferably made of some heat resistant material such as heat resistant cellulose acetate, so that it will not distort excessively due to prolonged contact of the segments 28 with the neck 12 of the cathode ray tube 10. The device 18 is also preferably made with the segments 28 molded because of the facility with which the plastic material described may be shaped by that method. The base portion 20 of the device 18 is molded with a plurality of circular ridges 35 which add structural strength to the base portion. It will be understood that any other mode of shaping which seems appropriate may also be employed.

Two annular permanent magnets 36 and 38 are used for centering of the electron beam of the tube 10. Two of the tapered segments 28 of the retaining device 18 are molded with tabs 44 and 46 on their outer surfaces. The spread dimension of the tabs 44 and 46 is made larger than the inner diameter of the magnets 36 and 38 so that when the magnets are pushed over the tabs 44 and 46 they become locked in place and cannot be removed from the retaining device 18 without forcibly compressing both of the tabs.

The base portion 20 of the retaining device 18 is provided with a pair of diametrically opposed bosses 48 and 50 which are molded at 90° positions relative to the tabs 44 and 46. The bosses 48 and 50 serve to back up the mounted magnets 36 and 38. The height of the bosses 48 and 50 determines the amount of spring bow that is

put into the magnets 36 and 38 after they are locked in position on the retaining device 18 by means of the tabs 44 and 46. The spring bowing of the magnets develops the necessary amount of friction on the magnets to lock them in position during shipping and normal vibration.

An annulus of non-magnetic anti-rotational sheet material (not shown) may be positioned between the two magnets 36 and 38. These magnets are mounted up against the bosses 48 and 50 adjacent the base portion 20 of the retaining device 18 and are independently rotatable about the axis of the neck 12 of the cathode ray tube. The magnets 36 and 38 are provided with ears 36A and 38A which extend beyond the periphery of the non-magnetic sheet material and facilitates turning of the magnets.

Although the invention has been described with reference to a specific embodiment, it will be obvious to those skilled in the art that it is not so limited but is susceptible to various changes and modifications without departing from the spirit and scope thereof.

I claim as my invention:

1. Beam centering apparatus for use in conjunction with a cathode ray tube having a neck portion, said beam centering apparatus comprising: a base portion having a central aperture through which the neck portion is adapted to pass and having a boss projecting from one side thereof, an integral flexible flange portion extending longitudinally from said one side of said base portion, said flange portion having at least one longitudinally extending slot therein, a pair of annular permanent magnets mounted coaxially side-by-side and surrounding said flange portion, and at least two tabs provided on the outer surface of said flange portion for urging said magnets axially towards said boss when said flange portion is laterally expanded so as to closely engage said neck portion of the tube.

2. Beam centering apparatus for use in conjunction with a cathode ray tube having a neck portion, said beam centering apparatus comprising: a base portion having a central aperture through which the neck portion is adapted to pass and having at least two bosses projecting from one side thereof, an integral flexible flange portion extending longitudinally from said one side of said base portion, said flange portion having at least one longitudinally extending slot therein, a pair of annular permanent magnets mounted coaxially side-by-side and surrounding said flange portion, and at least two tabs provided on the outer surface of said flange portion for urging said magnets axially towards said bosses when said flange portion is laterally expanded so as to closely engage said neck portion of the tube.

3. Beam centering apparatus for use in conjunction with a cathode ray tube having a neck portion, said beam centering apparatus comprising: a base portion having a central aperture through which the neck portion is adapted to pass and having a pair of diametrically opposed bosses projecting longitudinally from one side thereof, an integral flexible flange portion also extending longitudinally from said one side of said base portion, said flange portion having at least two segments tapered towards their free ends, a pair of annular permanent magnets mounted coaxially side-by-side and surrounding said flange portion, and a pair of tabs provided on diametrically opposed outer surfaces of said segments for urging said magnets axially towards said bosses when said segments are laterally expanded to closely engage the neck of the tube.

4. Beam centering apparatus for use in conjunction with a cathode ray tube having a neck portion, said beam centering apparatus comprising: a base portion having a central aperture through which the neck portion is adapted to pass and having a boss projecting from one side thereof, an integral flexible flange portion also extending longitudinally from one side of said base portion, said flange portion having at least two segments tapered toward their free ends, a pair of annular permanent magnets mounted coaxially side-by-side and surrounding said flange portion, and at least two tabs provided on the outer surface of said segments for holding said magnets against said boss and bowed-in towards said one side of said base portion when said segments are laterally expanded to closely engage said neck portion of the tube.

5. Beam centering apparatus for use in conjunction with a cathode ray tube having a neck portion, said beam centering apparatus comprising: a base portion having a central aperture through which the neck portion is adapted to pass and having a pair of diametrically opposed bosses projecting longitudinally from one side thereof, an integral flexible flange portion also extending longitudinally from said one side of said base portion, said flange portion having four segments tapered towards their free ends, a pair of annular permanent magnets mounted coaxially side-by-side and surrounding said flange portion, and a pair of tabs provided on diametrically opposed outer surfaces of two of said segments for urging said magnets axially towards said bosses when said segments are laterally expanded to closely engage said neck portion of the tube.

6. Beam centering apparatus for use in conjunction with a cathode ray tube having a neck portion, said beam centering apparatus comprising: a base portion having a central aperture through which the neck portion is adapted to pass, a flange portion extending longitudinally from one side of said base portion, said flange portion having at least one longitudinally extending slot therein, a pair of annular permanent magnets mounted coaxially side-by-side and surrounding said flange portion, and at least two tabs provided on the outer surface of said flange portion for retaining said magnets on said flange portion adjacent to said base portion.

7. Beam centering apparatus for use in conjunction with a cathode ray tube having a neck portion, said beam centering apparatus comprising: a base portion having a central aperture through which the neck portion is adapted to pass, a flange portion extending longitudinally from one side of said base portion, said flange portion having at least two segments tapered towards their free ends, a pair of annular permanent magnets mounted coaxially side-by-side and surrounding said flange portion, and a pair of tabs provided on diametrically opposed outer surfaces of said segments for urging said magnets axially towards said base portion.
